UNITED STATES PATENT OFFICE.

WILLIAM W. DEAN, OF CHICAGO, ILLINOIS, ASSIGNOR, BY MESNE ASSIGNMENTS, TO
BENJAMIN ELECTRIC MANUFACTURING COMPANY, OF CHICAGO, ILLINOIS, A COR-
PORATION OF ILLINOIS.

ELECTRIC HORN.

1,153,039.

Specification of Letter Patent. Patented Sept. 7, 1915.

Application filed October 15, 1913. Serial No. 795,345.

To all whom it may concern:

Be it known that I, WILLIAM W. DEAN, a citizen of the United States, residing at Chicago, in the county of Cook and State of Illinois, have invented new and useful Improvements in Electric Horns, of which the following is a full, clear, concise, and exact description, reference being had to the accompanying drawings, forming a part of

10 this specification.

My invention relates to improvements in electric horns or alarm signals, and has for one of its objects to improve the method of construction of such devices so that the 15 same may be more cheaply manufactured and the operation of the horn will be improved in various respects.

For the purpose of disclosing my invention I have illustrated in the accompanying 20 drawings one embodiment thereof.

In said drawings—Figure 1 is a sectional elevational view taken on the line 1—1 of Fig. 2; Fig. 2 is a rear view of the device with the casing removed; Fig. 3 is a sectional view taken on the line 3—3 of Fig. 2; and Fig. 4 is a diagrammatic view illustrating the instrument applied to a motor-driven vehicle, such, for instance, as an automobile.

30 The alarm or horn in the embodiment illustrated in the accompanying drawings is provided with a trumpet resonator or horn proper 10, which terminates in a flaring open end or mouth and is secured at its 35 inner end to the front portion 11 of the casing containing the working parts of the signal. This front portion of the casing is preferably stamped from sheet metal and is provided with a forwardly projecting 40 flange 12 around a central opening, to which flange the inner end of the horn is secured by soldering or spinning, or in any desired manner. The front section of the casing is provided with a rearwardly extending 45 peripheral flange 13, within which is adapted to telescope the edge of the rear section 14 of the casing. The front section of the casing has formed thereon a circular seat 15 on which the working parts of the 50 signal are adapted to be secured.

The sound is produced by a vibrating dia-

phragm 16 which is secured on the seat 15, a suitable ring or gasket 17, preferably formed of cork or cork composition, being interposed between the seat and the gasket. 55 The sound-producing diaphragm is preferably formed of a thin sheet of suitably tempered metal, and is of sufficient size to leave a clearance between its periphery and the flange 13 for the reception of the edge of the 60 casing 14.

The working parts of the horn are all mounted upon a suitable clamping ring 18 which is preferably formed of brass or some other suitable non-magnetic material. This 65 ring is of substantially the same outside diameter as the diaphragm and is secured in position by suitable screws 19 which are inserted through apertures in the front section of the casing and engage in the ring. 70 On this ring I mount a magnet and its associated parts for causing vibration of the diaphragm. The magnet is of particular construction and is especially adapted for the uses to which it is put. The core 20 of 75 the magnet consists of a plurality of laminations stamped of suitable sheet material in U-shape. These laminations are clamped together upon a shelf 21 on the clamping ring 18 by suitable screws 22 which pass 80 through the laminations and into the clamping ring, a clamping plate 23 being interposed between the heads of the screws and the top lamination to assist in holding the laminations in place. The ends of the core 85 or pole pieces of the magnet are chamfered or beveled off, as at 24, this result being obtained by making the legs of the laminations shorter on each succeeding lamination from bottom to top and slightly beveling the ends 90 of the legs. Each leg of the magnet core is provided with a coil or winding 25 which is wound in the form of a suitable spool and slipped over the legs of the core. Suitable coverings inclose the windings to protect 95 them from injury, and two of the terminals of the magnet are connected together, as by twisting the free ends of the windings together as at 26. By the above construction the poles of the magnet project inwardly 100 from the ring toward the center of the diaphragm and lie in a plane substantially par-

allel with the diaphragm, the shelf or support 12 raising the magnet sufficiently above the diaphragm to permit the parts to properly operate.

5 A tapper 27 which is adapted to strike the diaphragm for producing vibrations thereof is mounted upon the end of a soft iron plate 28, which in turn is riveted to the free end of a flat spring 29. This spring at its rear 10 end is clamped between a pair of clamping plates 30 and 31. The top surface of the plate 30 is beveled so that the rear end thereof is lower than the front end, while the bottom surface of the clamping plate 31 15 is oppositely beveled so that the rear end of the under surface is wider than the front end. By this arrangement the spring 29 is given a slight upward tilt so that the tapper 27 will be raised above the diaphragm 20 in normal position without the necessity of bending the spring 29. At the same time, the top surface of the clamping plate 31 is perfectly flat and is parallel with the top surface of the clamping ring 18. Immediately 25 above the tapper 27 is riveted or otherwise secured to the plate 28 the armature 33 of the magnet. This armature is formed of laminated plates and has its ends chamfered, as at 34, so that it overlaps the 30 chamfered ends 24 of the pole pieces of the magnet. This chamfered end construction is obtained by making each of the plates from the bottom to the top slightly longer, and slightly beveling the ends of the plate. 35 These laminated plates are clamped together by the same rivets which secure the armature in position upon the plate 28. It will be noted that the tapper 27 is so mounted on the plate 28 that it is centrally disposed 40 with respect to the armature 33, and is also disposed so as to be immediately over the center of the diaphragm.

The above described construction of magnet and armature adds materially to the efficiency of the magnet, and at the same time I am enabled to lay the magnet flatwise with respect to the diaphragm, that is, the legs of the magnet are substantially parallel with the diaphragm, whereby the depth of the 45 inclosing casing may be materially decreased. The free end of the armature adjacent the pole-pieces of the magnet, due to the inclined seat of its spring, is normally tilted away from the diaphragm so that the 50 energization of the magnet will move the armature toward the diaphragm.

The circuit for the magnet is interrupted by a vibrator which comprises a spring 35 which is clamped between a pair of bushings 36 and 37 on the screw 38 which passes through the bushings and into the clamping ring 18. The opening 39 in the spring through which the screw 38 passes is sufficiently large so that the spring will not

come in contact with the screw 38, and the 65 bushings are suitably insulated from the screw by means of an insulating washer 40 interposed between the bottom bushing and the clamping plate and an insulating washer 41 interposed between the head of the screw 70 and top bushing 37. This spring is electrically connected by the conductor 42 with one terminal of one of the windings 25. The end of the spring is provided with a platinum contact point 43 which is adapted to 75 make and break contact with the end of the contact screw 44. This contact screw is mounted on the end of an L-shaped plate 45, one leg of which is adapted to be clamped upon the top of the clamping plate 31 by 80 means of suitable screws 46 which pass through this leg and into the clamping ring 18. For insulating the plate 45 from the clamping plate 31, suitable insulating plates 47 are interposed therebetween and the 85 screws 46 are insulated from the plate by means of suitable insulating bushings 48. The screw 44 is adjustably supported in the end of one leg of the plate 45, and after having been adjusted to its proper position is 90 held in its adjusted position by a locking plate 49. This locking plate, it will be seen, is slightly tilted. One end thereof is provided with a threaded opening through which the screw 44 passes and the other end 95 rests on the plate 45. A suitable screw 50 secures the locking plate in this position, and when this screw 50 is drawn tight the screw 44 is absolutely locked against movement, and will remain in this adjusted position as long as desired. In event it is desired to set or adjust the screw 44, it is merely necessary to loosen the screw 50 to unlock the screw 44. The plate 45 is electrically connected by the conductor 51 with a 100 binding post plate 52 mounted upon an insulating bridge 53 secured by the screws 54 on the clamping plate 18. This binding post plate 52 carries a binding screw 55 which, together with the upturned lug 56 on the 105 binding post plate, forms a means for connecting one terminal of the line wire thereto. A second binding post plate 57, likewise provided with a binding screw 58, is mounted on the insulating support 53, and this plate 110 57 is connected by conductor 59 with one terminal of the magnet windings 25. The spring 35 is held in a normally raised position and with its contact in engagement with the screw 44 by means of an insulating button 60 mounted on the iron plate 28 and which engages the spring between its support and the contact.

It will be seen that in operation the circuit enters from one of the leading-in wires 115 to the binding post 58, thence it passes by conductor 59 to the coils of the magnets 25, thence by conductor 42 to the spring 35,

thence through the contact 43 and the screw 44 and plate 45, and back by conductor 51 to the opposite binding screw 55, and thence to the line. As soon as the magnet is energized and attracts its armature 33, causing the tapper to strike the diaphragm 16, the circuit is interrupted by permitting the spring 35 to draw down its contact 43 and open the circuit at the point where the contact 43 engages the screw 44. The circuit of the magnet is thus rapidly opened and closed and the tapper 27 caused to rapidly strike the diaphragm 16 to produce the required signal.

15 In Fig. 4 I have shown the horn or signal as applied to an automobile. Suitable conducting wires are shown as connecting the magnet of the horn with the batteries 61, and a suitable switch or circuit closing button 62 is shown placed upon the steering wheel of the automobile, whereby the circuit through the magnet may be controlled by the driver of the car.

It will be observed that in the drawings 25 the armature is inclined somewhat with respect to both the magnet and the diaphragm. It is to be understood, therefore, that where in the claims the armature is recited as being substantially parallel with the diaphragm, or in substantially the same plane as the magnet, what is meant is that the armature is sufficiently parallel with the diaphragm or sufficiently in the same plane of the magnet to be effectively acted upon by the magnet when the latter is energized, the magnet itself also being substantially parallel with the diaphragm.

While I have shown my signal or horn used in connection with a direct current supply, it will be understood that the magnet for operating the horn is just as efficient and may be used just as satisfactorily with alternating current; and while I have illustrated and described one embodiment of my horn, 45 it will be understood that various changes and modifications may be made therein without departing from the spirit of the invention as set forth in the accompanying claims.

50 Having thus described my invention, what I claim as new and desire to secure by Letters Patent, is:—

1. An electric horn comprising, in combination, a diaphragm, an electromagnet substantially parallel with the diaphragm, and an armature for said magnet mounted in substantially the same plane as the magnet normally tilted away from the diaphragm and having its free end adjacent the electromagnet and in a position to be drawn toward the diaphragm by said magnet.

2. An electric horn comprising, in combination, a diaphragm, an electromagnet mounted substantially parallel with said

diaphragm, an armature for said magnet radially disposed with respect thereto and having its free end adjacent the magnet and in a position to be drawn toward the diaphragm when the magnet is energized, a support, and a spring connected to said support and mounted on said support and normally tilting the armature away from the diaphragm.

3. An electric horn comprising, in combination, a diaphragm, an electromagnet supported substantially parallel with the diaphragm, an armature for said magnet, having its ends adjacent the poles of the magnet moved in a line crossing the axis of said poles and toward the diaphragm when the magnet is energized, a spring for said armature, a support, an inclined seat on said support for receiving one end of said spring to normally tilt the armature away from the diaphragm, and means for securing said spring on said seat.

4. An electric horn comprising, in combination, a diaphragm, an annular support, an electromagnet mounted on said support substantially parallel with the diaphragm, an armature for said magnet having its free ends adjacent the poles of the magnet and moved toward the diaphragm when the magnet is energized, and a spring for said armature connected at one end to said armature and having its other end secured on said support diametrically opposite the supporting point of the magnet and in a position to normally tilt the armature out of parallel with the axis of the poles of the magnet and away from the diaphragm.

5. An electric horn comprising, in combination, a diaphragm, a support, an electromagnet mounted on said support substantially parallel with the diaphragm, a plate, a spring secured at one end to said plate and having its opposite end mounted on said support, an armature on the opposite end of said plate, a contact-carrying spring mounted on said support and overlapping said plate, and a stationary contact member also mounted on said support and lying above said plate.

6. An electric horn comprising, in combination, a diaphragm, a support, an electromagnet mounted on said support parallel with the diaphragm, an armature, a spring for supporting said armature having one end secured to the support, a rigid clamp for securing said spring to said support having an extension, a circuit breaker and a stationary contact-adjusting screw for said circuit breaker for said magnet mounted on said extension.

7. An electric horn comprising, in combination, a diaphragm, a support, an electromagnet mounted on said support substantially parallel with the diaphragm and hav-

- ing its poles projecting inwardly toward the center of said diaphragm, an armature overlying the pole-pieces of the magnet on the side opposite the diaphragm and co-operating with the pole-pieces, and a spring mounted on said support adjacent the opposite edge of said diaphragm for supporting said armature.
8. An electric horn comprising, in combination, a diaphragm, an electromagnet operating said diaphragm, a current interrupter for said electromagnet comprising a movable contact, a stationary contact-adjusting screw, a support for said screw, a locking plate having an opening at one end through which said screw passes, and means for drawing the opposite end of the plate toward the support for locking said screw against rotation.
- 20 9. An electric horn comprising, in combination, a diaphragm, a clamping member engaging the diaphragm at its periphery and constituting a support, an electromagnet mounted on said support, and an armature for said magnet spring-mounted on said support, said magnet being substantially parallel with the diaphragm and having a pole extending toward the center of the diaphragm, said armature overlapping the pole and having its overlapping portion moved toward the diaphragm when the magnet is energized.
10. An electric horn comprising, in combination, a diaphragm, a clamping member engaging the diaphragm at its periphery and constituting a support, an electromagnet mounted on said support substantially parallel with the diaphragm and having its poles projecting inwardly toward the center of the diaphragm, an armature for said magnet overlying the poles of said magnet on the side opposite the diaphragm and in a position to be moved toward the diaphragm when the magnet is energized, and a supporting spring for said armature mounted on said support.
11. A compact shallow-backed electric horn comprising, in combination, a diaphragm, an annular support, an electromagnet mounted on said support flatwise with respect to said diaphragm and substantially parallel therewith, a flat armature also substantially parallel with the diaphragm and having one end spring-mounted on the support at a point opposite the point of support of the magnet and the other end adjacent the pole-pieces of the magnet and in a position to be moved toward the diaphragm when the magnet is energized.
- 60 12. In an electric horn, a diaphragm, an electromagnet mounted substantially parallel with the diaphragm, an armature mounted substantially parallel with the diaphragm and moved toward the diaphragm and in a direction traversing the ends of the

magnet when the magnet is energized, the said magnet and armature being oppositely supported with respect to the diaphragm, a spring normally retracting the armature, and means operated by the armature for 70 vibrating the diaphragm.

13. In an electric horn, a support, a diaphragm, an electromagnet substantially parallel with the diaphragm and mounted on the support adjacent one edge of the diaphragm, an armature also substantially parallel with the diaphragm and mounted on the support adjacent the opposite edge of the diaphragm and which when the electromagnet is energized is moved toward the diaphragm and tends to move into the same plane as the core of the electromagnet, a spring normally retracting the armature, and means operated by the armature for 80 vibrating the diaphragm.

14. In an electric horn, an annular support, a diaphragm, an electromagnet and armature mounted at opposite points on the support and both of which are substantially parallel with respect to the diaphragm, the 90 armature moving toward the diaphragm when the magnet is energized and having a diaphragm-vibrating tapper, and a spring normally retracting the armature, the armature extending inwardly toward the magnet 95 winding beyond the extremity of the magnet core.

15. In an electric horn, a diaphragm, an electromagnet and armature supported adjacent opposite edges of the diaphragm and 100 extending toward each other and both of which are substantially parallel with respect to the diaphragm and in a direction across the poles of the magnet, the armature being moved toward the diaphragm when the magnet is energized, and a spring normally 105 retracting the armature.

16. A compact shallow-backed electric horn comprising, in combination, a ring support, a diaphragm on the front side of said support, an electromagnet mounted on the rear side of said support with its coils and cores projecting over, parallel with and adjacent to the diaphragm, an armature for said electromagnet also mounted on said support and in position to be attracted by said magnet toward the diaphragm and toward the plane of the magnet cores, and a tapper carried by said armature to strike the diaphragm when so attracted.

17. An electric horn comprising a diaphragm in combination with a unitary self-contained structure comprising an annular support, an electromagnet for vibrating said diaphragm having its magnetic cores extending inward from said annular support, interrupter contact supports electrically independent of the armature of the electromagnet and mounted on said annular support, extending inward therefrom and in 130

a plane parallel with said diaphragm, and means for operating said contacts in response to the vibrations of said diaphragm.

18. An electric horn comprising, in combination, a diaphragm and an electromagnet for vibrating said diaphragm having its core lying in a plane substantially parallel to the plane of said diaphragm and having its armature lying in substantially the same

10 plane.

19. An electric horn comprising, in combination, a diaphragm, and an electromagnet for vibrating said diaphragm having its core lying in a plane substantially parallel to the plane of said diaphragm and having an armature lying in substantially the same plane, the ends of the pole pieces of said magnet and said armature being oppositely beveled.

20. An electric horn comprising, in combination, an annular support, an electromagnet having its pole pieces formed from a plurality of U-shaped laminations, beveled at its ends, the laminations being secured to said annular support by clamping the same upon the support at their bases, and an armature for vibrating said diaphragm comprising a plurality of laminations, beveled at its end, and a spring support for said armature.

21. An electric horn comprising a diaphragm in combination with a unitary self-contained structure comprising an annular support, an electromagnet lying in a plane substantially parallel to said diaphragm and extending inwardly from said annular support, an armature, a reed for supporting said armature secured on said annular ring at a point diametrically opposite the magnet, a stationary contact mounted on an arm extending inwardly from said annular support and a spring contact extending inwardly from said annular support, said contacts being moved into and out of engagement to control the circuit of said magnet by the movement of the armature.

22. An electric horn comprising, in combination, a diaphragm, an electromagnet for operating said diaphragm, the poles of said electromagnet comprising a plurality of U-shaped laminations lying in substantially parallel planes parallel with the diaphragm, and an armature operated by said electromagnet formed from a plurality of laminations, the adjacent edges of the pole-pieces of the magnet and of the armature being oppositely beveled.

23. An electric horn comprising, in combination, a diaphragm, a tapper, an armature movable to and from said diaphragm, a flat spring horizontally disposed for supporting said armature, a support for said spring comprising a pair of clamping plates having their clamping faces oppositely beveled to incline said spring upwardly and

away from said diaphragm, and an electromagnet for operating said armature.

24. An electric horn comprising, in combination, a diaphragm, an annular support, an electromagnet lying in a plane substantially parallel to said diaphragm and extending inwardly from said annular support, an armature, a flat spring for supporting said armature, a support for said spring comprising a pair of clamping plates having their clamping faces oppositely beveled to incline said spring upwardly from said diaphragm mounted on said annular support, and a tapper carried by said spring for striking said diaphragm.

25. An electric horn comprising, in combination, a diaphragm, an annular support, an electromagnet lying in a plane substantially parallel to said diaphragm and extending inwardly from said annular support, an armature, a reed for supporting said armature secured to said annular ring at a point diametrically opposite the magnet, a stationary contact mounted on an arm extending inwardly from said annular support, a spring contact carried by and extending inwardly from said annular support, said contacts being moved into and out of engagement to control the circuit of the magnet by the movement of the armature, an insulating bridge mounted on said annular support, a binding post mounted on said insulating bridge and electrically connected with said stationary contact, and a second binding post mounted on said insulating bridge electrically connected with one of the terminals of the windings of the magnet.

26. An electric horn comprising, in combination, a diaphragm, an annular support, an electromagnet lying in a plane substantially parallel to said diaphragm and extending inwardly from said annular support, an armature, a flat spring for supporting said armature, a support for said spring comprising a pair of clamping plates mounted on the annular support having their clamping faces oppositely beveled to incline said spring upwardly away from the diaphragm, a stationary contact, a support for said stationary contact comprising an L-shaped plate, one leg of said plate resting upon said clamping plates for said spring, and screws common to all of the plates for clamping all of said plates to the annular ring, a spring contact extending inwardly from said annular support, said spring and stationary contacts being moved into and out of engagement to control the circuit of said magnet by the movement of the armature.

27. An electric horn comprising, in combination, a diaphragm, an electromagnet for operating said diaphragm, a current interrupter for said electromagnet, comprising a movable contact, a stationary contact com-

prising a screw, a support for said screw, a locking plate having a screw-threaded opening through which said screw passes and supported from the support at the end provided with the opening, and means for drawing the opposite end of said plate toward the support for locking said screw against rotation.

In witness whereof, I have hereunto subscribed my name in the presence of two witnesses.

WILLIAM W. DEAN.
